CLAIM

The ornamental design for an aiming key golf putter attachment as shown and described.

DESCRIPTION

FIG. 1 is a top, right, front perspective view showing the aiming key golf putter attachment in use;

FIG. 2 is a top, right, and rear perspective view of the aiming key golf putter attachment of FIG. 1;

FIG. 3 is a top plan view of the aiming key golf putter attachment of FIG. 1;

FIG. 4 is a bottom plan view of the aiming key golf putter attachment of FIG. 1;

FIG. 5 is a front elevation view of the aiming key golf putter attachment of FIG. 1;

FIG. 6 is a rear elevation view of the aiming key golf putter attachment of FIG. 1;

FIG. 7 is a right side elevation view of the aiming key golf putter attachment of FIG. 1;

FIG. 8 is a left side elevation view of the aiming key golf putter attachment of FIG. 1; and,

FIG. 9 is a top plan view of a second embodiment of the aiming key golf putter attachment where the front, rear, right, and left elevation views are identical to FIGS. 5, 6, 7, and 8, respectively.

The broken lines shown in FIG. 1 depict the environment and form no part of the claimed design.

1 Claim, 4 Drawing Sheets
